J. L. GRETHER

FURNACE

Filed Nov. 5, 1923

Investor:
John L. Grether.
By H. G. Miller atty.

UNITED STATES PATENT OFFICE.

JOHN L. GRETHER, OF ST. LOUIS, MISSOURI, ASSIGNOR TO PAUL W. GRETHER, OF ST. LOUIS, MISSOURI.

FURNACE.

Application filed November 5, 1923. Serial No. 672,866.

The primary object of this invention is to provide certain improvements in a heating furnace or the like whereby a greater amount of heat is derived from a given 5 quantity of fuel.

Another object of the invention is in providing a heating furnace with an improved arrangement of discharging passageway for the discharge of the products of combustion 10 for increasing the heating efficiency of the furnace.

A further object of the invention is in providing improved means in a heating furnace for entraining the fresh air to and 15 from the heating chamber of the furnace.

A still further object of the invention is in providing a heating furnace with an improved form or method of associating the fresh air entraining passageways with the 20 products of combustion discharging passageway.

Other and further objects will appear in the specification and be specifically pointed out in the appended claims, reference being 25 had to the accompanying drawings, exemplifying the invention and in which:—

Figure 1 is a vertical section taken through this improved furnace.

Figure 2 is a horizontal section taken on 30 the line II—II of Fig. 1.

In the accompanying drawings, 1 designates a fire-pot which is surrounded by the usual fire-brick lining 2 and arranged above the fire-pot is the combustion chamber 3 and 35 located beneath the fire-pot 1 is the usual ash-pit 4 having the grate bars 5 arranged thereabove.

The fire-pot 1 and combustion chamber 3 are surrounded by a vertically extending 40 annular wall 6 and extending horizontally from said wall is a tubular extension 7 forming a passage 8 to enable the passing of fuel to the fire-pot when the fire-door 9 is opened. A passage 10 is provided for providing access to the ash-pit 4, said passage 45 10 being formed by the horizontally extending wall 11 which is also extended from the annular wall 6, said passage 10 being controlled by the ash-pit door 12.

50 Mounted on top of the annular wall 6 is a drum like structure 13, said structure 13 being larger in diameter than the combustion chamber 3 and having the upper extremity of its annular wall disposed out-

wardly beyond the lower extremity thereof 55 as designated at 14.

Mounted upon the upper edge of the annular disposed portion 14 and secured thereto by bolts such as 15 is an annular horizontally disposed portion 16 of a hollow member 17, said hollow member having a raised bottom portion 18, said bottom portion being held a distance above the horizontal portion 19 of the drum like structure 13, thereby providing a passageway 19^a. 60

The drum like structure 13 and the hollow member 17 are preferably cylindrical in shape, the hollow member 17 being smaller in diameter than the drum 13 and arranged in eccentric position to the drum 13. This 70 eccentric position of the drum 13 and the hollow member 17 to each other provides an annular passageway 20 between said drum and hollow member in which said passageway on one side is restricted as designated 75 at 21.

The outward disposition of the portion 14 of the drum 13 relative to the hollow member 17, provides an enlarged annular passageway 22, said passageway being much 80 larger in cross sectional area than the passageway 20 and leading from said enlarged passageway 22 is a discharge outlet 23 which discharges into the pipe or stack 24.

Surrounding the parts described is a 85 drum 25 forming an air heating chamber 26 and leading to said chamber at the lower end is a fresh air duct 27 and resting upon the upper edge of the drum 25 is a hot air receiving dome 28 from which a series of 90 hot air discharging flues 29 lead.

Depending from the under side of the hot air dome 28 is an intake pipe or flue 30, said flue having its open end depending within the hollow member 17. 95

In the operation of a furnace of this improved character, the products of combustion arising from the combustion chamber 3 will entrain upwardly and outwardly from the combustion chamber into the passageway 19^a and from there into the annular passageway 20 and upwardly to the enlarged annular passageway 22 and from said annular passageway 22 the products of combustion will be discharged through the 100 105 discharge outlet 23 into the stack 24.

The heated products of combustion from the fire-pot 3 while passing beneath the

2
raised bottom 18 of the hollow member 17 and while ascending the annular passageway 20 will thoroughly heat the walls of the hollow member 17 and the drum 13, said 5 walls therefore radiating a maximum of heat.

The fresh air entrained into the drum 25 through the duct 27 upon ascending upwardly in the drum 25 will surround the 10 heat giving off drum 13 and will be heated thereby, and as the air currents continue on upwardly within the drum 25 they will be entrained downwardly in the direction of the arrows 31 as they pass over the horizontal 15 portion 16 of the hollow member 17 and will be entrained into the heating chamber 32 provided by said hollow member thereby being further heated within said chamber.

20 After the air currents have been received within the heating chamber 32 they will be discharged therefrom into the intake flue 30 and into the hot air dome 28 from where they will be discharged into the distributing 25 flues 29 which lead from the hot air dome 28.

This manner of entraining the fresh air currents into peculiarly formed enclosures or passageways which are made from the 30 peculiar enclosing of the passageways through which the products of combustion are discharged, provides for a system of air entrainment in connection with a furnace in which a maximum heating efficiency is 35 given to the entrained air currents.

To eliminate short cutting of the travel of the products of combustion from the combustion chamber to the stack 24, the annular passageway 20 is restricted on one side as 40 designated at 21. In this instance the restriction on one side of the annular passageway 20 is provided by the hollow member 17 being disposed eccentric to the drum 13, the restriction being provided on the 45 stack side of the furnace, said restricted side of the annular passageway forcing the ascending products of combustion to travel upwardly annularly within the passageway 20.

50 What I claim is:—

1. A furnace comprising a surrounding drum, a fire-pot arranged within said drum, a hollow member closed at its lower end arranged above said fire-pot, a surrounding 55 wall extending from said fire-pot around said member arranged so as to provide an encircling passageway which is restricted on one side for the discharging of the products of combustion from said fire-pot, a chamber formed above said hollow member, and an intake flue leading to said chamber.

2. A furnace comprising a surrounding drum, a fire-pot arranged within said drum, a hollow member closed at its lower end arranged above said fire-pot, a surrounding 60

wall extending from said fire-pot around said member arranged so as to provide an encircling passageway which is narrower on one side than on its opposite side for the discharging of the products of combustion 70 from said fire-pot, a chamber formed above said hollow member, and an intake flue leading to said chamber depending within said hollow member.

3. In a hot air furnace the combination 75 of a combustion chamber, a hollow member closed at its lower end located above said chamber, a wall surrounding said hollow member in offset relation thereto thereby providing an encircling passageway for the so discharge of the products of combustion from said chamber, an outlet flue leading from said hollow member, and means provided by said hollow member and said flue whereby air currents will be introduced into 85 said hollow member beneath said flue.

4. In a hot air furnace the combination of a surrounding drum, a combustion chamber located within said drum, a hollow member closed at its lower end located above said 90 chamber, a wall surrounding said hollow member in offset relation thereto thereby providing an encircling passageway for the discharge of the products of combustion from said chamber, an outlet flue leading 95 from said hollow member, means provided by said hollow member and said flue whereby air currents will be introduced into said hollow member beneath said flue, and a discharge pipe leading from said encircling 100 passageway.

5. In a furnace the combination of a combustion chamber, a hollow member closed at its lower end located above said chamber, a wall surrounding said hollow member thereby providing an annular passageway which leads from said combustion chamber, said passageway being restricted on one side, a discharge pipe leading from said passageway on the restricted side thereof, and an 105 outlet flue co-operable with said hollow member.

6. In a furnace the combination of a combustion chamber, a hollow member closed at its lower end located above said chamber, 110 a wall surrounding said hollow member thereby providing an annular passageway which leads from said combustion chamber, said passageway being restricted on one side, a discharge pipe leading from said passageway on the restricted side thereof, an outlet flue depended within said hollow member, 115 said flue being smaller in diameter than said hollow member, and a drum arranged surrounding of said combustion chamber and 120 said surrounding wall.

7. In a furnace the combination of a combustion chamber, a hollow member closed at its lower end located above said chamber, a wall surrounding said hollow member there- 125

by providing an annular passageway which leads from said combustion chamber, said wall at its upper end being disposed outwardly thereby forming an annular enlargement, said passageway being restricted on one side, a discharge pipe leading from said annular enlargement on the restricted side of said passageway, an outlet flue co-operable with said hollow member and a drum 5 embracing said combustion chamber and said surrounding wall.

8. In a furnace the combination of a combustion chamber, a hollow member closed at

its lower end located above said chamber, a wall surrounding said hollow member there- 15 by providing an annular passageway which leads from said combustion chamber, said passageway being restricted on one side, said wall at its upper end being disposed outwardly, thereby forming an annular en- 20 largement, a discharge pipe leading from said annular enlargement in proximity to the restricted side of said passageway, and a drum embracing said combustion chamber and said surrounding wall.

JOHN L. GRETHER.
